Primary Examiner — Leah Macchiarolo*Assistant Examiner* — Evin F Ershock(74) Attorney, Agent, or Firm — Coffield Heedy Kilgore PLLC; William Heedy(57) CLAIM

The ornamental design for a scrubber brush, as shown and described.

DESCRIPTION

FIG. 1 is a perspective view of a scrubber brush, showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines in FIGS. 1-7 illustrate portions of the scrubber brush that form no part of the claimed design.
